UNITED STATES PATENT OFFICE.

ISAAC C. POPPER, OF NEW YORK, N. Y.

DESIGN FOR A COOKING KIT.

53,155.

Specification for Design.

Patented Apr. 1, 1919.

Application filed February 26, 1918. Serial No. 219,318. Term of patent 14 years.

To all whom it may concern:

Be it known that I, ISAAC C. POPPER, a citizen of the United States, residing at New York city, in the county of New York and State of New York, have invented a new, original, and ornamental Design for a Cooking Kit, of which the following is a specification, reference being had to the accompanying drawing, forming part thereof.

The figure is a perspective view of a cooking kit, showing my new design.

I claim:

The ornamental design for a cooking kit, as shown.

ISAAC C. POPPER.
